UNITED STATES PATENT OFFICE.

JOSEPH FISK, OF MANISTEE, MICHIGAN.

CABINET.

No. 832,601.

Specification of Letters Patent.

Patented Oct. 9, 1906.

Application filed August 11, 1905. Serial No. 273,801.

To all whom it may concern:

Be it known that I, JOSEPH FISK, a citizen of the United States, residing at Manistee, in the county of Manistee and State of Michigan, have invented a new and useful Improvement in Cabinets, of which the following is a specification.

This invention relates to cabinets designed for holding and displaying articles of merchandise, and especially laces, ribbons, and all classes of fabrics adapted to be rolled or wound upon a frame.

The invention consists of a central standard, arms radiating from the standard, movable frames carried by said arms, and rotatable wire frames carried by the movable frames and adapted to hold the goods displayed.

The invention also consists in the novel features of construction and combination of parts hereinafter described, pointed out in the claims, and shown in the accompanying drawings, in which—

Figure 1 is a perspective view of my device in use. Fig. 2 is a plan view, clips and signs being removed. Fig. 3 is an enlarged detail elevation of a portion of the device. Fig. 4 is a detail view, partly in section, showing the manner of holding the frames in the arms. Fig. 5 is a detail perspective view showing the construction of the frame and arm with track-section. Fig. 6 is a sectional view on the line 6 6 of Fig. 7, showing the manner of securing the rotatable frames in the movable frames. Fig. 7 is a section on the line 7 7 of Fig. 6. Fig. 8 is a section on the line 8 8 of Fig. 6. Fig. 9 is a detail perspective view of a portion of the end of one of the rotatable frames.

In the drawings, A represents a base having a standard A', fixed or rotatable, as may be desired, which standard carries circular platforms A² and A³. On the upper face of the platform A² is arranged a plurality of radial arms B, and similar arms B are carried by the under face of the platform A³, all of the arms extending beyond the platform and in a horizontal plane. The arms carry vertically-arranged cog-tracks B' on their upper and lower faces, respectively. The upper arms B also carry adjacent their outer ends clips C or any other suitable means for holding placards C'. Resting on the lower arms B and held between the lower and upper arms are slidable rectangular frames D,

the top and bottom members of the frames being grooved, as shown at D', to receive a portion of the track-sections.

The top and bottom members of the frame D extend inwardly beyond the frame, and a vertical rod E is journaled in the extended portions and at one side of the groove D'. These rods, of which there will be as many as there are frames, carry pinions or spur-gears E' at their upper and lower ends, which pinions mesh with the upper and lower cog-tracks B', respectively. The gears E' at the upper ends of the rods mesh or engage with the cog portion of the track B' carried by the upper arms B, and those at the lower ends engage the track B' carried by the lower arms B.

The side members of the frames D are longitudinally, grooved as shown at D², and provided with a plurality of transverse intersecting grooves D³, and plates G are arranged over the said grooves and are formed with a slot G' terminating in a recess G², which registers with the groove D², over which the plate rests. Each plate G has an inwardly-extending lug G³, through which works a plunger H, having a head H' and actuated by a spring H², secured at one end to the plunger and bearing at the opposite end on the uppermost lug G³. To hold the lace or other articles of merchandise to be displayed, I provide a plurality of preferably wire frames J, which at each end have a projecting tongue J', and these supplemental frames J are arranged transversely in the frames D, several to each frame, the tongues extending into the grooves D² and resting in the recesses G² of the plates G. The frames are held in position by means of the plungers H, the heads of which bear downwardly on the inner end portions of the tongues and prevent them from rising in the recesses G² or from rotating. The tension of the springs H², however, is not sufficient to prevent the frames J from being lifted out of place when it is desired to remove them.

The object of the tracks and spur-gears is to give a positive, steady, and uniform movement to the frames when it is desired to draw them outwardly and slide them back into position, and all tendency on the part of the frames to bind is thus obviated. Any suitable material may be employed in constructing the device and any number of main or supplemental frames employed.

Having thus fully described my invention, what I claim as new, and desire to secure by Letters Patent, is—

1. A device of the kind described comprising a central standard, a plurality of radially-extending cog-track sections extending from said standard and arranged in upper and lower sets, a plurality of frames arranged between the upper and lower track-sections, spur-gears carried by the frame adapted to engage the cogs of the tracks, and means carried by the frames for displaying merchandise.
2. A cabinet of the kind described, comprising a standard, upper and lower platforms carried by the standard, radially-arranged track-sections carried by said platforms, a plurality of open frames held upon said track-sections and movable toward and away from the standard, and supplemental frames arranged in the first-mentioned frames and adapted to hold articles of merchandise.
3. A cabinet of the kind described comprising a plurality of movable rectangular frames having their side members longitudinally grooved upon their inner faces, a plurality of supplemental rectangular frames adapted to rest transversely within the

frames first mentioned, each of said supplemental frames having a flat projecting tongue at each end, said tongues being adapted to extend into the longitudinal groove, plates carried by the first-mentioned frame and covering the groove, the said plates having recesses in which the tongues of the supplemental frames rest, and a spring-pressed plunger carried by the said plates and working in the groove and adapted to bear upon the said tongues, as and for the purpose mentioned.

4. A device of the kind described comprising a plurality of radially-arranged open frames, a plurality of cog-track sections arranged adjacent said frames, spur-gears carried by the frames and adapted to engage said tracks, and a plurality of transversely-arranged detachable, supplemental frames carried by each of the first-mentioned frames and adapted to carry articles of merchandise wound thereon as and for the purpose set forth.

JOSEPH FISK.
